Inventor
Bror E. Cederstrom

By his Attorney, Great Western

UNITED STATES PATENT OFFICE.

BROR E. CEDERSTROM, OF DETROIT, MICHIGAN, ASSIGNOR TO MORGAN & WRIGHT, A CORPORATION OF MICHIGAN.

GOVERNOR.

1,343,389.

Specification of Letters Patent. Patented June 15, 1920.

Application filed May 3, 1915. Serial No. 25,657.

To all whom it may concern:

Be it known that I, BROR E. CEDERSTROM, a citizen of the United States, residing at Detroit, county of Wayne, and State of Michigan, have invented certain new and useful Improvements in Governors, of which the following is a full, clear, and exact description.

This invention relates to governors and more specifically to tension regulating devices and has for an object to provide a device for automatically maintaining a predetermined tension in a traveling web from a stock supply to a point where it is to be operated upon or used.

The invention will be readily understood from the following description taken in connection with the accompanying drawings in which—

Figure 1 is a side elevation of the device; and

Fig. 2 is an end elevation with portions in section.

Referring now to the drawing in which like characters of reference designate similar parts, 10 designates a support. A bracket 11 is secured to the support and a stub-shaft 12 is rotatably mounted on the bracket, the stub-shaft having an angular socket in one end to receive the spindle 13 upon which the stock roll 14 of fabric or other material is spooled. The web of material passes from the stock roll 14 underneath guide rollers 15 and 16 carried by the bracket 11 and over an intermediate guide roll 17 yieldably held by a tension device hereinafter described, and from the guide roller 16, passes to the point where it is to be used, as for example, to the rolls of a calender for treating the web with a plastic, or to a ring core in case the web consists of rubber-treated fabric which is being used to build a tire. In either case the web is drawn positively from the stock roll by the apparatus operating upon or using the material, thereby rotating the stock roll 14, spindle 13 and shaft 12 as a unit.

For retarding rotation of the stock roll and thereby tensioning the web, a friction brake is mounted on the shaft 12. The brake comprises a casing 18 which has a stationary disk wall 19, against which a friction disk 20 is automatically pressed at times, as will be presently explained, there being a spring 20' which acts on the fric-

tion disk against said automatically applied pressure and serves to release the brake after each application. The friction disk is formed in sections to facilitate assembling, all of the sections being feathered upon the 60 shaft 12 and being movable as a unit thereon toward and away from the wall 19.

For applying the friction brake, a cylinder 21 is mounted on the casing 18 and is partially filled with liquid such as oil. Compressed air, or other medium under pressure, is let into the cylinder and acting through the oil, causes the latter to exert pressure through a port 23 in the cylinder against a piston 23' directly on the rear side of the 70 brake disk, thereby moving the latter into frictional engagement with the wall 19. The admission and release of the air is effected through a valve chest 24 within which is rotatably mounted a valve 25 that is held 75 in its seat by a spring 30.

The valve 25 is formed with a port 28' which during rotation of the valve in one direction comes into registration with a port 31 formed in the top of the cylinder and 80 admits compressed air from a pipe 32 to the cylinder on top of the oil. Also formed in the valve is a passage 33 which, upon rotation of the valve in the other direction, establishes communication between the port 85 31 and an exhaust port 34 whereby the compressed air is allowed to escape from the cylinder. This admission and release of the air pressure from on top of the oil correspondingly applies the friction brake or 90 permits of release of the friction brake by the action of its spring 20.

For automatically operating the valve, I provide a bell crank lever 26, one leg of which is connected to the valve by means 95 of a connecting rod 27 and a crank 28 on the valve stem. The other leg of the lever is connected to a helical spring 36 which is connected to the above mentioned roller 17 by a link mechanism 35 and yieldably holds 100 said roller at its upper limit of movement. An indicator 40 is operatively interpolated between the spring and the link mechanism to indicate the degree of tension in the web.

In operation, suppose the web to be initially started into the machine whereby it is to be operated upon or used. At first there will be no tension on the web and under this condition the port 28' of the valve will be in registration with the port 31 in the 110

cylinder and the compressed air will be acting through the oil to hold the brake set and the stock roll 14 stationary. During initial feed of the web, the roller 17 will be drawn 5 downwardly against the pull of the spring 36, with a resultant movement of the bell crank lever 26, connecting rod 27 and crank 28, until at a predetermined point in this movement (at which point the necessary or 10 predetermined degree of tension will exist in the web), the port 28' in the valve will pass out of registry with the port 31, thereby shutting off the compressed air, and the passage 33 will establish communication be- 15 tween the port 31 and the exhaust port 34, thereby releasing the brake and allowing the stock roll 14 to rotate. As soon as the tension on the web slackens below said pre- 20 determined degree, the above described movement of the parts is reversed, where- upon the air is again admitted to the cylinder and the brake set until the desired tension is restored in the web.

For adjusting the parts to properly time 25 the valve, so that any desired degree of tension may be maintained in the fabric, I provide an adjusting nut 37, which is threaded onto an eyebolt 38 to which the spring 36 is attached, and bears against the bracket 39 30 of the eyebolt, as shown.

Having described my invention, what I claim and desire to protect by Letters Patent is:

1. In a device of the character described, 35 a pair of brake-members, one of said mem- bers being fixed and the other of said mem-

bers being mounted for rotation with a shaft to be controlled and also movable relatively thereto, resilient means normally tending to hold said members spaced apart, a chamber 40 containing liquid, a piston in engagement with said movable member and actuated by said liquid, and means to apply pressure to said liquid to thereby move the rotatable brake-member into frictional engagement 45 with the stationary brake-member.

2. In a governor, a shaft, a fixed brake member, a brake disk mounted to turn with said shaft and slidably thereon toward and from said brake member, a chamber 50 containing a liquid adapted to actuate said brake disk, a piston interposed between said brake disk and the liquid, said piston and disk being relatively rotatable, means for supplying fluid under pressure, and means 55 automatically movable in accordance with the movement of said shaft for admitting said pressure fluid to the liquid containing chamber or for opening an exhaust passage from said chamber.

3. In a governor, a shaft, a brake disk mounted to turn with said shaft and slidably thereon, a fixed brake member on one side of said brake disk, a liquid containing chamber on the other side thereof, means utilizing gaseous fluid for exerting pressure on 60 said liquid to apply the brake disk to the brake member, and resilient means for returning the brake disk to inoperative position.

Signed at Detroit, Mich., April 27th 1915.
BROR E. CEDERSTROM.
